UNITED STATES PATENT OFFICE

153,299

DESIGN FOR A COMB

Eugene J. Lux, New York, N. Y., assignor to Columbia ProtektoSite Co., Inc., Carlstadt, N. J., a corporation of New Jersey

Application March 15, 1947, Serial No. 137,641

Term of patent 7 years

(Cl. D86—8)

To all whom it may concern:

Be it known that I, Eugene J. Lux, a citizen of the United States, and resident of New York city, in the county of New York and State of New York, have invented a new, original, and ornamental Design for a Comb, of which the following is a specification, reference being had to the accompanying drawing, forming a part thereof, and of which Fig. 1 is a side view of a comb, showing my new design; Fig. 2 is a top plan view thereof; Fig. 3 is an end view; and Fig. 4 is a sectional view on the line 4—4 of Fig. 1.

The dominant features of the design consist in the parts shown in full lines.

I claim:

The ornamental design for a comb, substantially as shown and described.

EUGENE J. LUX.
